his ATTORNEY

UNITED STATES PATENT OFFICE

FRANK WOLF, OF NEW YORK, N. Y.

ATTACHMENT FOR CONTAINERS

Application filed December 24, 1928. Serial No. 228,102.

This invention relates to an attachment for containers; and particularly for collapsible tubes the contents of which are discharged by squeezing the tube, which has an outlet 5 nipple threaded to receive the usual cap so that the tube can be ordinarily kept closed when not needed.

An object of the invention is to provide an attachment to be placed on the conical top 10 of the tube and designed to be held in place by suitable parts, such as a stand or holder for the tube, engaging the attachment at opposite sides; or by a ring or the like which encircles the tube and attachment, or by other 15 means. The top has a bead-flange at its periphery which cooperates with said means to hold the attachment in position.

The invention is clearly set forth in the following description and drawings: but I reserve the right to make changes which do not go beyond the principle of the invention or exceed the scope of the appended claims.

On the drawings,

Figure 1 is a side view of an attachment according to my invention in combination with a collapsible tube;

Figure 2 is a view of what is shown in Figure 1, seen from the left;

Figure 3 shows a modification;

Figures 4, 5 and 6 are, respectively, a top, a side and a sectional view, of another form of the invention;

Figures 7 and 8 illustrate in side view two additional modifications.

The same numerals identify the same parts throughout.

The numeral 1 on Figures 1 and 2 indicates a collapsible tube with a soft body and the usual comparatively rigid conical top 2 bearing a discharge nipple 3. The outer edge or periphery of the top projects beyond the circumference of the flexible body of the tube, forming a flange or bead 4. The attachment 5 which is put over the top may have the form of a cover with a discharge nozzle 6, to receive the neck 3.

To support this tube I may utilize a stand comprising a pair of legs 7 pivotally or otherwise movably attached to a base 8, and the upper ends 9 of these legs may be wid-

ened somewhat and have transverse grooves 10 on their inner faces to receive the bead-flange and the cover 5. The lower sides of these grooves form shoulders which pass under the bead 4 so that the tube is held upright in the stand. To get the tube in the stand, the legs 7 are separated so that the tube bearing the cover 5 can be placed between the legs 7 and then the legs 7 are moved toward the tube to make the ends 9 engage the edge of the cover and the flange 4. To hold the legs in this position the stand may have a retaining ring 11, with bearing sleeves 12 that slide on the legs and adapted to encircle the tube 1. The legs 7 normally diverge in a downward direction, and the ring is of such size that when it is moved down, the legs are forced to grip the tube between them; and when it is moved up the legs are separated enough to release the tube. Other means for engaging and releasing the legs may of course be employed.

The nozzle 6 which fits over the nipple 3 forms an extension thereof. This neck mounts an arm 13 which carries a valve or the like 14 with a cork or rubber gasket 15. The arm 14 is pivoted at 16 at the side of the neck and has a handle 17. When the handle 17 is pressed the valve 14 can be moved and the contents of the tube expelled through the nozzle 6.

The cover 5 bearing the nozzle 6 and the valve closure 14 is thus fitted to the top of the tube and held in place by the parts 9 of the legs 7. Whenever the contents of the tube are wanted, the handle 17 is depressed to lift the cap valve closure 14 and then the tube is squeezed to discharge some of the contents through the nozzle 6. So long as the legs are in gripping position the stand supporting the tube and the element or cover 5 cannot be taken off, but when the attachment is to be removed, the legs 7 must first be released and swung apart far enough to enable the outer edge of the cover to clear the grooves 10 in the upper ends 9 of the legs 7.

Figure 3 shows in side elevation a similar cover 5a with a nozzle 6a having a pivoted valve closure 14a attached to an arm 13a, pivoted at 16a on lugs 18 at the sides of this

nozzle 6a, and with a handle so that the cap 14a can be raised. The arm 13a and the nozzle 6a have engaging lugs 19 and 20, respectively, to keep the valve closed. In this form, however, the cover 5a is provided with a depending rim 21 which is cut at several points; or instead of a rim a number of projections extending downward past the flange 4, may be used. These projections may have their lower ends turned outward and to hold the cover on, I resort to a stand comprising two curved gripping parts 22 on a pair of legs 23. This stand is of the same construction as that described in my application Serial No. 247,500, filed January 18, 1928. It is made of the parts 22 and the legs 23 which are in the form of frames, each frame comprising a pair of opposite side portions, the upper ends being joined by the parts 22, and the legs 23 being pivoted together. When they are moved to separate the ends 22 the member 5a is released; and when moved in the opposite direction the parts 22 engage the rim 21 and hold the cover in place. This form of attachment is fully set forth in my copending application Serial No. 300,892, for closures for collapsible tubes and other receptacles, filed August 20, 1928, of which this case is in part a continuation.

In Figures 4, 5 and 6, the attachment or cover 5b has a central extension or neck 25 with an opening therethrough to be put upon and enclose the neck 3 of the tube. To hold the cover on, a binding device or ring indicated at 26 is provided, this device comprising curved sections 27 which are pivoted to the attachment at 28, and shaped so as to be concave on their inner faces. Thus when the retaining device is applied, the ring in question surrounds the outer edge of the cover 5b and the lower edge of the ring encircles the tube but just below the flange 4. Hence the cover 5b cannot be pulled off because the ring 26 holds it fast. The opposite ends of the sections of the ring can be secured by a catch 29, which engages a stop 30. With this form the cover can be taken off and put on easily, and it is held fast by the catch 26, which is releasable to permit the ring to be loosened and the cover to be removed when necessary. This form of attachment is disclosed in my copending application, Serial No. 247,999, for accessory devices for collapsible tubes, filed July 23, 1928, whereof this case is a continuation to that extent.

In Figure 7 I show another form of cover 5c with discharge nozzle 6a to be fitted upon the top and outlet neck 3 of the tube. The cover carries a valve 14a and operating arm 13a as before, but the edge 24 of the cover is extended downward and is bent or crimped over the flange 4 of the top 2. The cover thus is held on and an additional stand or retaining ring is not needed. This form is also dis-

closed in my copending application Serial No. 300,892, above-mentioned.

In Figure 8, the cover 5d is similar to the member 5b in Figures 4, 5 and 6, but the rim 31 has inside guides 32 to screw upon the flange 4. The guides or threads 32 may be interrupted or continuous and have any desired cross-sectional shape. The guides 32 are shown in Figure 8 of the drawings in the nature of screw threads. But they may be simply separated non-continuous guides arranged in spaced rotation around the inside of the cap with a slight inclination to act as a screw thread usually acts.

The attachment or cover in all forms protects the top 2, and helps it to maintain its shape so that only the tube 1 is deformed in use. The attachment also provides the nozzle enclosing the neck 3, to cover the threads on the neck and prevent lodgment of the contents and dust on the neck, thus preventing uncleanliness; and serves further to mount a valve or closure for the tube 1, as desired. The attachment is secured largely through the instrumentality of the flange 4.

In Figures 1 to 6, inclusive, the parts which engage the rim of the attachment or cover may be made to fit tight enough to compress or indent the tube 1, below the flange to give a secure hold, and the same result may be obtained with the attachment of Figure 7.

I claim:

1. An attachment for a collapsible tube with a soft body and a comparatively rigid top having an outlet nipple at the center and a bead-flange at the periphery of the top; the attachment being shaped to be put over said top and to constitute a sheathing for said top and outlet nozzle, and retaining means adapted to afford and maintain an engagement with the attachment to hold it in place on the bead flange.

2. An attachment for a collapsible tube having a soft body and a rigid top, with a central nipple on the top and a bead-flange around the periphery of the latter, the attachment being shaped to have the form of a cover to fit upon the top, and a central nozzle to receive the nipple, and a retaining device to grip the attachment at its lower periphery, and hold same on the tube.

3. An attachment for a soft collapsible tube having a rigid top with a bead-flange around the outer periphery of the top, said attachment comprising a cover to be fitted on said top, a frame structure for the tube including a pair of members shaped to engage the edge of the cover, the cover having an outlet nozzle, and connecting means between said members to maintain an effective engagement between said members and the edge of the cover.

4. An attachment for a soft collapsible tube having a rigid top with a bead-flange around its periphery, and a central discharge

nipple, a cover on said top, means binding the edge of said cover to said flange, a nozzle projecting from the cover and surrounding the nipple on the top, and a pivoted valve 5 cap on the neck of the cover to open and close the end of said nozzle, the attachment protecting said top.

5. An attachment according to claim 3 wherein the cover terminates at the flange.

10 6. An attachment for a soft collapsible tube having a rigid top with a bead-flange around its periphery and a central outlet nipple, the attachment comprising a cover to be fitted on said top and having a discharge nozzle, a closure on said nozzle to control the latter, said cover being extended downward to come in juxtaposition to the flange of the top, and a frame structure for the tube having parts at its upper end bent to grip the cover 15 circumferentially where it comes in juxtaposition to the flange.

7. An attachment for a soft collapsible tube having a rigid top with a bead-flange surrounding its periphery and a central discharge nipple, the attachment comprising a cover to protect the top and having a discharge nozzle to receive the nipple of the tube, a pivoted closure from the end of said nozzle mounted thereon and an arm to manipulate 20 said closure, the cover having its outer edge bent downward over the flange against the tube.

8. The attachment according to claim 7, wherein the downward bent end of the cover 25 permanently engages the flange on its under side and secures the cover in place.

9. An attachment for a soft collapsible tube having a rigid conical top end with a central discharge nipple and a peripheral bead-flange, said attachment comprising a cover to be fitted on said top to protect the latter and having a nozzle into which the nipple of the tube extends, and a pair of oppositely disposed pivoted members with a shape to embrace and clamp together the edge of the cover and said bead, and means associated 40 with said pivoted members whereby to secure the same firmly in the position in which they clamp the embraced edge of the cover and 45 bead-flange.

50 10. An attachment for a soft collapsible tube having a rigid top, with a bead-flange at its periphery, said attachment comprising a cover to fit upon said top, and a stand comprising legs having their upper ends shaped to engage the edge of the cover, and bind it 55 upon said top.

11. The attachment according to claim 3 wherein the means for engaging the legs has 60 the form of a movable ring.

In testimony that I claim the foregoing as my invention, I have signed my name hereto.

FRANK WOLF.
